To all whom it may concern:

Be it known that I, ELIZABETH COYLE, a citizen of the United States, residing in the city of St. Louis, in the State of Missouri, have invented and produced a new, original, and ornamental Design for a Pillow or Cushion Top, of which the following is a full, clear, and exact description, reference being had to the accompanying drawing, forming part of this specification.

The drawing is a face view showing my new design.

As shown in the drawing, the leading or material features of my design consist of a background illustrating the facade of a peristyle having bases at the bottom of the columns

and an arch above them. At one side of the arch is the figure of a woman representative of poetry and at the opposite side of the arch is the figure of a woman representative of art. In front of the background is the figure of a woman shown in a pose indicating welcome. At each side of the background are representations of bowls in which plants are illustrated.

I claim as my invention—

The ornamental design for a pillow or cushion top herein shown and described.

ELIZABETH COYLE.
